UNITED STATES PATENT OFFICE.

HENRY B. BRADFORD, OF EDGEMOOR, DELAWARE, ASSIGNOR TO EDGE MOOR IRON COMPANY, OF EDGEMOOR, DELAWARE, A CORPORATION OF DELAWARE.

BOILER DEFLECTOR-WALL.

1,355,807.

Specification of Letters Patent. Patented Oct. 19, 1920.

Application filed August 17, 1917. Serial No. 186,684.

To all whom it may concern:

Be it known that I, HENRY B. BRADFORD, a citizen of the United States of America, residing in Edgemoor, in the county of New Castle and State of Delaware, have invented 5 certain new and useful Improvements in Boiler Deflector-Walls, of which the following is a true and exact specification, reference being had to the accompanying drawings, which form a part thereof.

My present invention has for its general object to provide a simple, durable and effective wall construction of a refractory character especially adapted for use on the deflector walls extending across the tubes of a water tube boiler. More specifically the object of the invention is to provide a tile facing 15 for a deflector wall which can be readily installed and will not work apart under the vibration to which the boiler tubes traversed by the wall are subjected.

The various features of novelty which characterize my invention are pointed out with particularity in the claims annexed 25 hereto and forming a part of this specification. For a better understanding of the invention, however, and the advantages possessed by it, reference should be had to the accompanying drawings and descriptive matter in which I have illustrated and 30 described preferred embodiments of my invention.

Of the drawings:

Figure 1 is a somewhat conventional elevation of a water tube boiler provided with 35 a deflector wall, constructed in accordance with the present invention.

Fig. 2 is a front elevation of a portion of the deflector wall of the boiler shown in 40 Fig. 1.

Fig. 3 a section taken on the line 3—3 of Fig. 2.

Fig. 4 is a section taken on the line 4—4 of Fig. 2.

Fig. 5 is a section taken on the line 5—5 of Fig. 2.

Fig. 6 is an elevation of a portion of a boiler having a deflector wall of modified construction.

Fig. 7 is a section taken on the line 7—7 of Fig. 6.

Fig. 8 is an elevation of one of the tiles employed in the wall shown by Figs. 6 and 7.

Fig. 9 is a partial section taken on the line 9—9 of Fig. 8. 55

Fig. 10 is a fragmentary view showing a cross section through one of the tubes forming the baffle wall E, and through two of the upper row of tubes on which wall E is supported and one of the next row of tubes, 60 showing also one of the tiles I, and a manner in which the upper row of such tiles I are held in place by the wall E. Fig. 11 is a side elevation of the parts shown in Fig. 10, with the tiles E', tiles I, and the baffle 65 wall of which tiles I form a facing shown in vertical section.

The water tube boiler conventionally illustrated in Fig. 1 comprises front and rear headers AA connected by water tubes B. 70 The intertube space is divided into three passes by front and rear deflector walls C and D respectively, which in the construction shown in Fig. 1 are perpendicular to the tubes B. A short deflector wall E rests 75 upon the top row of tubes B immediately in front of the front deflector C, the upper edge of the latter being in engagement with the wall E. The wall E is preferably made up of tiles E', as shown in Figs. 10 and 11. The 80 deflector wall D may be of any usual or suitable construction. The deflector wall C, in the construction of which the present invention is used, comprises, as shown, a skeleton reinforcing structure or backing formed of 85 cast iron sections F which may be of any usual construction. At the rear of the sections F is a layer or coating G of the refractory mortar known as "hot blast cement," and the front sides of the sections F are 90 covered with a thinner coating G² of the same material. In front of the coating G² is a layer of similar tiles I, which are each diamond shaped and formed with cylindrical grooves I² at each corner to receive portions of corresponding water tubes B. In 95 the particular form of the wall C, shown in the drawings, soot blower pipes H are embedded in the hot blast cement wall layer G and are secured to the cast iron sections F by the eyebolts H², and are provided at intervals with nozzles H'. Washers H³ surrounding the nozzles H' are advantageously interposed between the pipes H and sections F. The sections F are formed with apertures F² to receive nipples H', and the ends 100 105

of the eyebolts H². The sections F may be of any convenient form, such, for instance, as is shown in Fig. 2 of my former Patent 1,069,105 of August 5, 1913 where together they make up an interior metallic wall of the baffle wall. Each of the tiles I is formed with a central aperture I' and the nipples H' project into some of these apertures. Some of these central apertures also receive 10 portions of the ends of the eyebolts H² and the nuts secured thereon.

The tiles I are specially shaped to interlock with one another so as to prevent the individual tiles from moving relatively to 15 one another in a direction parallel to the water tubes B. This interlocking effect is obtained with the tiles I by the special inclination given to edge surfaces I³, I⁴, I⁵ and I⁶ of each tile, those surfaces contacting 20 with the corresponding edge surfaces of adjacent tiles in the assembled wall as shown in Figs. 2 and 3. To obtain the desired interlocking effect the edge surfaces I³, I⁴, I⁵ and I⁶ of each tile I are each inclined at an oblique angle to the planes of the flat faces of the tile. The inclination of each of the surfaces I³ and I⁴ is such that these surfaces if extended, would intersect a line passing through the center of the tile 25 perpendicularly to its front faces, at a certain distance in front of the wall C. The edge surfaces I⁵ and I⁶ on the other hand would, if extended, intersect the said perpendicular line at a similar distance at the 30 rear of the tile. In consequence each tile I in the wall C, when viewed from the front side, has its two edge surfaces I³ and I⁴ overlapped by the edge surfaces I⁶ and I⁵ respectively of two other tiles I, and has 35 its edge surfaces I⁵ and I⁶ overlapping the edge surfaces I⁴ and I³ respectively of two other tiles I. In consequence of this arrangement no lower tile I can be moved forward without carrying with it the two tiles 40 in the row above it. The tiles of the uppermost row are held against a forward movement by the wall E in the construction shown, and in consequence it is impossible for any tile to move forward away from its 45 normal position in the wall. The interlocking of the tiles to prevent the individual tiles from moving away from the body portion of the deflector of which they form a part overcomes a curious tendency which 50 has been found to exist in practice for the individual tiles when not interlocked, to creep forward along the water tubes with which they are in engagement. The tendency of the tiles to creep forward is due, 55 I believe, to the vibration to which the boiler tubes are subjected under certain conditions of operation. Whatever the cause may be, the creeping tendency of the tiles which is ordinarily less marked in the 60 case of the upper and lower rows of tubes 65

than in the case of the intermediate tubes, has in the past given rise to a good deal of trouble which is avoided by the use of the special tile construction which I have devised.

When the deflector wall does not embody 70 soot blower pipes all of the central apertures I' in the tiles I may advantageously be filled with hot blast cement, and where the soot blower pipes are employed I ordinarily prefer to fill all of these central apertures except those receiving the blast nozzles H' with hot blast cement after the tiles are put in place. To give ample clearance 75 for the nuts on the eye bolts H² the inner ends of the central passages I' are advantageously enlarged as indicated at I¹⁰. 80

In Figs. 6 to 9, inclusive, I have illustrated a tile construction for use in a deflector wall which is not perpendicular but inclined at an oblique angle to the boiler tubes B extending through the tubular wall. The tiles IA, illustrated in Figs. 6 to 9, inclusive, are characterized by the fact that each of the edge surfaces I³⁰, I⁴⁰, I⁵⁰, and I⁶⁰ is a plane perpendicular to the flat sides 85 of the tile. While in the assembled tile wall the edges of adjacent tiles do not interlock to prevent movement of one tile relatively to the others in a direction perpendicular to the planes of the flat sides, the water tubes prevent such movement of the 90 tiles, and the edges of the tiles do interlock to prevent movement of the tiles in a direction parallel to the lengths of the water 95 tubes. So far as movement in a direction parallel to the water tubes is concerned the surfaces I³⁰, and I⁴⁰ of each tile are overlapped by the surfaces I⁶⁰ and I⁵⁰ respectively of the two upper tiles, and the surfaces I⁵⁰ and I⁶⁰ overlap the surfaces I⁴⁰ and I³⁰ respectively of each lower tile, so 100 that exactly the same interlocking effect is obtained with the tile IA when set in a wall inclined to the boiler tubes, as is obtained 105 with the tile I when set in a wall perpendicular to the water tubes. 110

While in accordance with the provisions of the statutes I have illustrated and described the best form of my invention now known to me, it will be apparent to those skilled in the art that changes may be made in the form of my invention without departing from its spirit, and that some features of my invention may be sometimes used to advantage without a corresponding use of other features of the invention. 115

Having now described my invention, what I claim as new and desire to secure by Letters Patent, is:

1. In a water tube boiler, the combination with the water tubes of a deflector wall comprising a layer of similarly shaped tiles, each notched at its edges to receive portions of a plurality of said tubes, and having 120 125 130

edge surfaces between the notches, so formed that they will overlap the adjacent edge surfaces of adjacent tiles so that each tile other than the marginal tiles of the wall is prevented by the adjacent tiles from movement along the water tubes in a direction parallel to the length of the latter.

2. In a water tube boiler, the combination with the water tubes of a deflector wall 10 comprising a layer of tiles, each notched at its edges to receive portions of a plurality of said tubes, and having edge surfaces between the notches, which are so inclined to the direction of the water tubes that some 15 of said edge surfaces if extended would intersect a line parallel to the water tubes passing centrally through said tile in front

of the layer of said tiles, while others would intersect said line at the rear of the tiles.

3. A tile for use in forming deflector wall 20 of a water tube boiler formed with transverse grooves at its edges to receive portions of a plurality of boiler tubes, and having edge surfaces between the grooves which are inclined in different directions with respect to the axes of said grooves.

4. A tile for use in forming the deflector wall of a water tube boiler formed with transverse grooves at its edges to receive portions of a plurality of boiler tubes, and 30 having flat edge surfaces between the notches, which are inclined in different directions to the side faces of the tile.

HENRY B. BRADFORD.
